(57) **CLAIM**

The ornamental design for a pair of eyeglass temples, as shown and described.

DESCRIPTION

FIG. 1 is a perspective view of a pair of eyeglass temples design showing my new design.

FIG. 2 is a perspective view of a pair of eyeglass temples from an oblique bottom angle.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines shown in the drawings depict portions of a pair of eyeglass temples in which the design is embodied that form no part of claimed design.
